UNITED STATES PATENT OFFICE.

JAMES A. ALLEN, OF PHILADELPHIA, PENNSYLVANIA.

DESIGN FOR A BLOCK OF STENCIL-INK.

SPECIFICATION forming part of Design No. 27,746, dated October 19, 1897.

Application filed August 31, 1897. Serial No. 650,198. Term of patent 14 years.

To all whom it may concern:

Be it known that I, JAMES A. ALLEN, a citizen of the United States, residing in the city and county of Philadelphia, State of Pennsylvania, have invented and produced a new and original Design for a Block of Stencil-Ink, of which the following is a specification, reference being had to the accompanying drawings, forming part thereof.

10 The leading features of my design for a block of stencil-ink are, first, the elliptical form of the block in plan view; next, the convex top of the block; next, the sloping sides of the block, and, finally, the corrugated bottom of the block.

15 Figure 1 represents a perspective view of

a block of stencil-ink embodying my design. Fig. 2 represents a transverse vertical section thereof.

In the drawings, A designates a block of stencil-ink, the same being of elliptical form in plan view and having a convex top B, sloping sides C, and a corrugated bottom D.

Having described my invention, what I claim as new, and desire to secure by Letters Patent, is—

The design for a block of stencil-ink, as herein shown and described.

JAMES A. ALLEN.
